UNITED STATES PATENT OFFICE.

JOSEPH R. WATERS, OF PRINCESS ANNE, MARYLAND.

DEVICE FOR HOLDING PROTECTORS UPON THE EDGES OF COATS, &c.

1,222,250.

Specification of Letters Patent. Patented Apr. 10, 1917.

Application filed April 8, 1916. Serial No. 89,908.

To all whom it may concern:

Be it known that I, JOSEPH R. WATERS, a citizen of the United States, residing at Princess Anne, in the county of Somerset and 5 State of Maryland, have invented certain new and useful Improvements in Devices for Holding Protectors Upon the Edges of Coats, &c.; and I do hereby declare the following to be a full, clear, and exact description 10 of the invention, such as will enable others skilled in the art to which it appertains to make and use the same, reference being had to the accompanying drawings, and to the letters and figures of reference marked 15 thereon, which form a part of this specification.

This invention relates to new and useful improvements in devices for holding protectors upon the edges of coats and consists 20 of a simple and efficient device of this nature having various details of construction, combinations and arrangements of parts, which will be hereinafter fully described, shown in the accompanying drawings and 25 then specifically defined in the appended claim.

My invention is illustrated in the accompanying drawings, in which:—

Figure 1 is a view of a coat showing the 30 application of my invention as holding a protector upon the edges of the coat.

Fig. 2 is a sectional view on line 2—2 of Fig. 1.

Fig. 3 is a detail perspective view of the 35 holding device.

Reference now being had to the details of the drawings by letter, D designates the holding piece made of a single piece of wire having a straight shank portion D⁶, bent to 40 form oppositely disposed loops D⁴, and the

wire at corresponding ends of the loops is bent to form the resilient bail-shaped portions D'. Each end of a bail-shaped portion terminates in an eye D² through which the shank portion D⁵ passes. 45

In Fig. 1 of the drawings, I have illustrated a coat A with a collar A' and lapel A², and the projecting devices B, shown as held over the meeting edges of the coat, the edges being held near to each other by the 50 loops B' which engage over the buttons B². To support the protecting device, a strap C is fastened at C' to the ends of the protecting devices and passes underneath the lapel and collar. 55

In applying the holding device, the protectors are adjusted as shown in Fig. 1 and the resilient bail-shaped members of the holder sprung over the meeting edges of the coat opposite each other with the straight 60 shank portions D⁵ engaging the edges of the coat. The resiliency of said bail-shaped members will tend to hold the protecting device frictionally in place. 65

What I claim to be new is:— 70

A device for holding a protector over the edges of coats, consisting of a single piece of wire having a straight shank portion bent to form oppositely disposed loops, the wire at corresponding ends of the loops being 75 bent to form resilient bail-shaped portions, each end of the wire bent to form an eye engaging the straight shank portion of the wire intermediate the loops.

In testimony whereof I hereunto affix my signature in presence of two witnesses.

JOSEPH R. WATERS.
